UNITED STATES PATENT OFFICE.

WILLIAM F. WOOLARD, OF WAUWATOSA, WISCONSIN.

CORRUGATED-METAL END FOR RAILWAY-CARS.

1,398,249.

Specification of Letters Patent. Patented Nov. 29, 1921.

Application filed April 16, 1921. Serial No. 461,766.

To all whom it may concern:

Be it known that I, WILLIAM F. WOOLARD, a citizen of the United States, and a resident of the city of Wauwatosa, county 5 of Milwaukee, and State of Wisconsin, have invented a certain new and useful Improvement in Corrugated-Metal Ends for Railway-Cars; and I do declare the following to be a clear, exact, and complete de- 10 scription thereof, such as will enable persons skilled in the art to which the invention pertains to make and use the same, reference being had to the accompanying drawing for an illustration of one form in 15 which my invention may be embodied in reducing it to practice.

My invention relates to a corrugated metal end unit for railway freight cars, and comprises a car end unit embodying certain 20 dominant features of construction which will be hereinafter described in detail, and the novelty of which will be pointed out in the appended claims.

In the drawing which accompanies this 25 specification—

Figure 1 is a horizontal sectional view on the line 1—1, Fig. 2, showing the preferred form of my improved corner post, with a portion of the corrugated end plate in correct 30 relation thereto, the view showing also in dotted lines a portion of the car structure.

Fig. 2 is a view in elevation of a portion of one end of a car end unit, in the construction of which my improved corner post 35 is incorporated.

Fig. 3 is a vertical sectional view on the line 3—3, Fig. 2, showing the configuration of the post, and the application of the corrugated end plate thereto.

Fig. 4 is a fragmentary section on the line 4—4, Fig. 2, showing more clearly the manner of forming the corrugations upon 40 the end flange of the post.

Fig. 5 is a view in elevation of the interior of a section of the post, looking in the direction of the arrow A in Fig. 1, showing the side and end flanges of the post, with the groove in the angle formed by the converging flanges, and showing also how 50 the corrugations in the end flange of the post gradually merge into the angle thereof.

Fig. 6 is a horizontal sectional view showing a modified form of my invention.

At the present time, there are in operation by the railroads of the United States 55 approximately 2,600,000 freight cars. Of

this number, some 200,000 have been equipped with corrugated metal ends under governmental direction. This feature of construction is now being incorporated in 60 new cars under specifications by the master car builders, and is likewise applied to old cars when necessity arises for repair thereof, it having been ascertained by test and experience that a horizontally corrugated car end possesses the greatest powers of resistance attainable in structures of this 65 class.

The metallic end structure now being applied to railway cars is a development 70 which has arisen from a situation brought about by changing conditions. The air-pressure control with which all railway trains are now equipped has produced the changed conditions referred to. Hereto- 75 fore, freight cars were generally constructed of wood, on account of the availability and cheapness thereof, and the absence of any perfection of the idea of utilizing a metallic end structure, or any 80 knowledge as to the desirability thereof. Formerly, the time and distance within which moving freight trains were brought to a state of rest by the now obsolete types of braking devices then employed, were each 85 comparatively long. As a result of the gradual bringing of the freight train to this condition of rest, there was but little shifting of the load in the cars, and consequently the wooden ends of the cars were 90 not damaged by the movement of the load.

With the introduction and modern equipment of all trains with air-brakes, the distance within which a freight train may be brought to a halt is materially lessened, 95 with a corresponding decrease of the time within which the stop is made. One of the results of these new conditions is that a shifting of the load is unavoidable, unless secured against movement within the 100 car. However, certain classes of freight, the momentum of which is beyond control, are shifted in the stopping of the train, so that the ends of the car are damaged and in many instances completely destroyed. 105

These adverse conditions resulting from the more rapid movement of freight trains and the shortening of the time and distance within which the same are now brought to a condition of rest, has stimulated the introduction of improvements in the end structure of freight cars, with a view to over- 110

coming the former objections and eliminating the resultant damage to the cars, and the master car builders have quite naturally turned from wood to metal by reason 5 of the greater powers of resistance of the latter material, in their efforts to meet the exigencies of the situation and produce a satisfactory construction.

Flat metal plates reinforced and supported 10 in various ways, have been employed in car end constructions, but they only in an incomplete manner meet the requirements of the situation, on account of the lack of rigidity in car ends so constructed, and their general 15 inability to resist the destructive strains to which they are subjected by the shifting of the mass of the material constituting the load. Metal plates, bars, rods, beams and channels, in particular, as well as lumber, 20 exert a destructive force upon the ends of the cars in which they are loaded, by reason of the impossibility of securing such loads against shifting movement, or restraining the momentum of the mass when the train 25 is slowed up or halted.

The earlier use of flat metal plates in the construction of car ends has been followed by the use of corrugated metal plates, which possess greatly increased resisting properties 30 due to their formation, which provides against lateral deflection, as is well known. These corrugated plates have assumed almost every conceivable form, and have been found to overcome the difficulties and 35 objections heretofore existing, and to answer all of the requirements for rigidity and strength, so that the corrugated type of car end construction is now accepted as offering a solution of a vexatious problem.

40 Corrugated metal end plates for railway cars are divisible into two types, when viewed from a constructional standpoint. The first type embraces plates having corrugations, whatever may be their form, which 45 do not extend from edge to edge of the plate, but which terminate within the dimensional lines thereof, so as to leave plane marginal surfaces on the plates adjacent the corrugations, which plane margins constitute a 50 convenient and ready means of attachment of the end plate to the car. This type of corrugated plate, however, is quite difficult of construction, as will be later pointed out. The second type embraces plates having parallel 55 corrugations which extend from edge to edge of the plate, so that two opposite corrugated margins are presented. Although the second type of corrugated plate is much more simple in the matter of its 60 production, a difficulty exists in providing satisfactory and convenient adjunctive means for attaching an end plate so corrugated to the car. Such attaching means necessarily must be provided with correlated 65 corrugations of such form as to permit a

proper assemblage and union to be established between the parts. The difficulties encountered in the manufacture of suitable attaching means for end plates of the latter type will be explained farther on.

End plates having corrugations which terminate within the horizontal dimensions of the plate, leaving plane surfaces upon the side margins of the plate adjacent the ends of the horizontal corrugations formed 70 therein, for providing an advantageous means of attaching the plates to the body of the car, are now generally employed. But the advantages of simplicity of attachment thus obtained, are more than offset by the 75 disproportionately large attendant expense and the difficult operations necessarily performed in producing a large plate with horizontal corrugations, the length of which is less than the full width of the plate in which 80 they are formed. It being mechanically impossible to press the very large corrugations in a cold plate of the dimensions required, without exceeding the elastic limits of the plate and producing a condition in which 85 the molecular integrity of the plate is destroyed, it is necessary that the plate be brought to a proper state of ductility by first heating the plate in a furnace.

But while the plates have been heated so as 90 to enable the easier formation of the corrugations therein, this later practice is beset by the same serious objection mentioned, and in many cases the elastic limit of the metal is likewise exceeded in forming the corrugations, so that parts of the structure thereof are stretched to such an extent that their 95 integrity is impaired in a very large measure. The plates are thus very seriously weakened, and are deprived of the essentials of rigidity 100 and strength in such a degree as to affect their serviceability and endurance. At best, and under the most favorable conditions, the initial rigidity of the plate is greatly lessened by the annealing which 105 occurs in heating the plate.

Moreover, the production of car end plates having corrugations which do not reach the side margins of the plates in which they are formed, as described herein, necessitates 115 the installation of enormous and powerful presses, capable of exerting a pressure of many thousands of tons. The costs involved in the erection and operation of such presses, coupled with the fuel and labor costs involved 120 in the heating of such plates, and the difficulties attendant upon the manipulation of the very large heated plates for action thereon by the presses, are factors which contribute to an excessive cost of production of 125 plates corrugated in this manner. The only advantage which follows from the practice outlined, is that the plane margins of the plates at the end of the corrugations may be attached to the flanged corner pieces of the 130

car with facility. But this apparent advantage presents nothing possessing a substantial reality, for it has no compensation for the structural disadvantages which follow from the distortion and consequent weakening of the sheet metal in producing corrugations the length of which is less than the width of the metal plate in which they are formed.

10 It is recognized by the master car builders, whose judgments comprise consideration of both serviceability and cost, that an ideal construction of devices of this class is one in which the metal sheet used in the formation 15 of the end plate of a railway freight car is corrugated from edge to edge in the direction of the width of the plate. A freight car end embodying as an element an end plate of this type, when formed from a flat plate of suitable gage, is declared to meet in the fullest 20 measure all of the requirements imposed thereon in the traffic. A plate so corrugated may be produced without any distortion of the metal, such as is inevitable and inseparable from the practice of the methods 25 previously described. It is comparatively a simple matter to corrugate a metal plate throughout its area, or so that the successive corrugations will be made to extend from 30 one edge of the plate to the other. This result may be achieved without heating the plate, and without subjecting the metal of the plate to any tensile stresses or distortion, by which operation the molecular integrity 35 of the structure of the plate is destroyed. The desirable result stated may also be achieved without the use of the powerful presses, costly in construction and expensive in operation, or the heating furnaces, which 40 have heretofore been required in producing corrugations less in length than the width of the plates in which they are formed. An end plate corrugated over its entire area may be produced from a cold plate by passing 45 the same through a pair of fluted rollers, which will form the corrugations without stretching the metal. This operation does not detract from the preservation in the largest possible measure of its entirety, the 50 molecular integrity of the plate as it leaves the rolling mill. The fluted rollers act to produce corrugations which are uniform in their formation, so that after the plate passes through the rollers it is not necessary to subject the same to any other treatment, other than that which is incident to the formation 55 of the attaching rivet holes therein.

While as hereinbefore stated, a car end formed from a metal plate corrugated from 60 edge to edge as described, is declared to be ideal, viewed from the standpoint of efficiency and cost of production, such structures have not come into general use. In studying the situation, I have discovered 65 that a serious obstacle preventing the use

of such plates, resides in the inability to perfect a feasible plan for connecting or attaching to their supporting members the plates thus corrugated, although several attempts appear in the art to have been made 70 with that purpose in view. To be acceptable in matters of construction and cost, such attaching means must be in the form of an angular member pressed from a steel plate of proportionate gage with the grain 75 of the metal running with the plate, one flange of which member is corrugated to correspond and to engage and interlock with the corrugations of the end plate of the car, and the other flange of which is preferably formed as a plan surface to embrace and be easily attached to the side of the car. The formation of a flanged member as described, is accompanied by peculiar conditions which are difficult to overcome in the 80 production of a corner piece possessing the requisite degree of strength, by reason of the excessive distortion unavoidably imposed upon the metal in forming the corrugated flange, which difficulties and consequent objections do not appear to have been surmounted heretofore.

A patent granted in 1916 discloses the idea of the construction of a car end composed of a plate having corrugations extending 95 from edge to edge thereof. In the said patent, a cast steel corner post of peculiar formation for engaging the corrugations of the end plate is described, but such a post does not appear to meet the requirements of the 100 present situation, by reason of the inability to secure uniformity in the structure of castings, and the limitations imposed upon the elasticity thereof. The causes of lack of uniformity in a series of like castings are 105 well known, and a post having the structural features recited could not be produced as a stamping from a metal plate in which the grain of the metal extends longitudinal thereof, or in a direction transverse to that 110 in which the greatest stress occurs.

A patent granted in 1917 discloses a car end plate having the formation just described. The said patent describes an angular corner piece, one flange of which is corrugated to receive the corrugations of the 115 end plate of the car, and the other flange of which is formed as a plane to bear against the side thereof. The corrugations of the end flange of the corner piece are shown as 120 extending to the angle thereof, but it is difficult to form the corrugations in the relation shown without an undue distortion of the metal of the corner piece, because of the extent of the displacement of the metal 125 which must unavoidably take place in producing corrugations of a depth which will accommodate those of the end plate of the car. No reserve of metal can be drawn upon in forming the abrupt corrugations in the 130

flange, and an undue weakening of the metal in the region of the corrugations in the corner piece is thus produced, by reason of the excessive tensile stresses to which the 5 metal is subjected in the process of production of the corrugations.

A patent granted in 1919 presents a similar construction, with the corrugations of the end flange of the corner piece somewhat 10 removed from the angle thereof. But the objection adverted to as existing in the prior structure is not overcome, inasmuch as there exists in the latter structure the same undue displacement of the metal in the formation 15 of the corrugated flange, by reason of the lack of any reserve of metal which can be drawn upon in forming the corrugations. The channels constituting the corrugations are formed with abrupt ends as before, and 20 this construction subjects the metal to a like distortion, with consequent weakening of the structure.

In my studies conducted with a view to 25 overcoming the objections existing in known structures, I have found that a car end plate corrugated from edge to edge thereof in the manner now greatly to be preferred, may be successfully and satisfactorily used with a corner post of special construction, in 30 which the difficulties of manufacture heretofore encountered and the inherent weaknesses of former structures of corner members are completely eliminated.

In its preferred form, my improved corner post is formed as a pressed-steel angular member with the grain of the metal running in the direction of the length thereof, with flanges of the corner post standing approximately 90° apart, and joined in such 40 manner as to form a groove lengthwise of the post in the interior angle thereof. It is preferable from a manufacturing standpoint, that the groove in the angle formed by the convergence of the laterally extending flanges of the corner post be of circular cross section, so as to produce upon the exterior angle of the post a corresponding straight, rounded rib extending longitudinally of the post. The semi-tubular construction thus produced contributes an additional element of strength to the post. One 50 of the flanges is preferably formed as a plane surface, to embrace the side of the car and be easily attached thereto, as heretofore. The other or end flange of the post is corrugated on transverse lines corresponding exactly with the corrugations of the end plate, so that the corrugations of the parts will engage and interlock when the posts are 60 attached to the end plate, one post to be attached to each vertical edge of the end plate, to constitute a complete car end unit.

The provision of the longitudinal groove in the interior angle of the corner post provides a reserve area of metal which may be

drawn upon in forming the corrugations in the end flange of the post, such corrugations gradually merging into the groove, so that the metal of the flange is but slightly displaced in producing the corrugations, and this is effected without approaching the elastic limit of the material. In my improved construction, there occurs no violent and abrupt distortion of the molecular structure of the metal, such as would have the effect 75 of weakening the same.

Having outlined the nature of my invention in the foregoing, I will now describe a specific embodiment thereof which I have chosen to illustrate. In the drawing, the numerals 10 and 11 designate, respectively, portions of the side and end of the frame of a railway car, the end plate 12 of which is corrugated horizontally from edge to edge thereof. My improved corner post is indicated by the numeral 13. This post may be pressed into angular cross-sectional form from a flat steel plate of any suitable gage, possessing the strength and rigidity necessary to the satisfactory performance of its purposes, although a plate having a gage of 0.3125" will ordinarily be sufficient. Instead of producing a right angle at the junction of the flanges, I enlarge the structure of the angle into a semi-tubular formation 14 so as to provide upon the exterior of the post a pronounced rounded rib 15, and an interior groove 16, from which semi-tubular formation the angularly disposed flanges 17 and 18 extend laterally. The side flange 17 may be formed as a plane surface adapted to bear upon and be secured to the side of the car at the end thereof. The end flange 18 is corrugated transversely as before stated, the corrugations extending from the edge of the flange toward the angle and being gradually merged into the groove thereat. It will be observed that the end flange 18 is a gradual development out of one side of the semi-tubular portion 14, so that the connecting portion of the flange 18 and the semi-tubular portion 14 does not abruptly depart from the vertical plane of the said flange. This construction creates a reserve of metal which may be drawn upon in producing the corrugations of the flange 18, and enables such corrugations to be formed in the flange without unduly straining the metal of the corner post.

As a result, the end flange 18 of the post may be corrugated without subjecting the metal to the tensional stresses which are incident to the abrupt formation of corrugations of the older structures. The corrugations may therefore be formed as parallel 125 channels of uniform depth and width throughout their length from the edge of the flange to the flare, wholly clear from obstructive angles, so that the three parts constituting the end unit may be assembled 130

with greater facility. The corrugated end plate will be attached to the corrugated posts by means of rivets passed through perforations in the parts, one of such rivets being 5 shown at 19.

In practice, the corrugated flange of the corner posts will overlap the outer margins of the corrugated end plate, although a reverse of this arrangement may be resorted 10 to, if desired. In either construction, the rounded longitudinally extending ribs 15, which are quite pronounced, serve to create a setting for the end plate, which lies within the vertical plane formed by the meeting 15 of the tangential lines extending from the rounded exterior formation of the corner posts, and thus is produced a paneled effect of pleasing appearance.

Fig. 6 shows a modification of the structure in which the angle formed by the laterally extending flanges of the corrugated post is made to approach more closely a tubular formation, by reducing the distance by which the said flanges are separated, so 25 as to permit the end plate to be applied to the exterior surface of the flanges of the posts, and at the same time bring such plate within the parallel tangents of the tubular formation. The paneled effect produced by 30 the rounded ribs, before described, is not detracted from. The modification also enables a side plate to be attached to the other flange of the post, in the same relative position.

35 The corrugated end plates may be formed from a single sheet of suitable dimensions and of a gage which will enable it to resist the stresses imposed in the shifting of the load when the train is stopped. A steel 40 plate having a gage of 0.25" will ordinarily be sufficient. But if the end plate be composed of a plurality of sections, the upper section may be made of thinner gage material, the two sections forming the end 45 plate being united along a horizontal line, as is customary in present day car construction, and as shown in Patent No. 1,031,571, July 2, 1912. The corrugated posts may be attached at their lower ends to the sills of 50 the car, as shown in Patent No. 1,208,928, December 19, 1916, and may be anchored in place by means of diagonal members, as shown in Patent No. 1,070,380, August 12, 1913. This arrangement will constitute a 55 rigid structure which will successfully resist the destructive force of the shifting load, but will be free from liability to fracture because of the elastic nature of the steel employed.

60 By forming the corner posts from sheet steel with the grain thereof running in the direction of the length of the post, a maximum strength in the structure is secured, inasmuch as the stresses are applied in lines 65 opposed by the greatest resistance. A

pressed steel corner post is further advantageous in that such maximum strength is attained by the use of a structure much lighter than could be obtained in a cast steel post of inelastic formation of much greater 70 weight.

While I have described the flanges of the corner post as standing approximately at an angle of 90°, it is obvious that the degree of angularity of the end flanges may 75 be varied from the longitudinal line of the car within reasonable limits, and while I have specified in some of my claims that the said flanges are spaced 90° apart, it is to be understood that I do not limit myself to 80 such exact spacing.

My present invention has enabled me to construct a corrugated metal car end unit of maximum strength and durability and at a greatly reduced cost. At the same time I 85 am able to produce such a car end unit without the installation of heating furnaces and powerful presses, the constructional and operating costs of which, constituting an excess, are chargeable against the product. 90 By my improvement, I am also enabled to construct an angular corner post with transverse corrugations on one of its flanges, without attacking the integrity of the fabricated post, and so produce a corrugated corner post for freight cars possessing a degree of strength not heretofore attainable in 95 similar structures.

The joints between the end plate and the posts should be heavily slushed with metallic paint to exclude moisture.

Although I have previously stated that the corrugations co-extensive with the lateral dimensions of the end plate may be produced by cold rolling, it is obvious that such 105 corrugations may be formed by hot or cold pressing, or as a final operation upon the heated plate at the rolling mill. The transverse corrugations may be formed upon the corner post either by cold pressing or hot 110 pressing, as may be found expedient, both methods being entirely practicable in connection with the present construction, in which the corrugated flange of the post is always provided with a reserve supply of 115 metal which may be drawn upon for the gradual formation of the flaring corrugations, without the excessive distortion and abrupt displacement of the metal heretofore described as incident to the production of 120 prior structures.

I have deemed it sufficient for the purpose of making clear the disclosure of the invention, to show the framing of the car in a merely conventional manner, inasmuch as 125 the structure thereof and the methods of applying the invention thereto, are matters within the common knowledge of those to whom this specification is addressed.

Having thus described my invention, what 130

° I claim and desire to secure by Letters Patent of the United States, is:

1. The framing of a railway car, in combination with a metallic end plate corrugated from edge to edge, and a pair of pressed-steel corner posts for attaching the edges of the plate to the framing, said posts each having angular flanges and a longitudinal groove in the angle thereof, one flange of each post being corrugated on lines parallel to the corrugations of the end plate, the said corrugations on the post gradually merging into the groove in the angle thereof, the end plate and the posts being connected with the corrugations on the parts engaged and interlocked.

2. The framing of a railway car, in combination with a metallic end plate corrugated from edge to edge, and a pair of pressed-steel corner posts for attaching the edges of the plate to the framing, said posts each having angular flanges, one flange of each post being corrugated on lines parallel to the corrugations of the end plate, the said corrugations on the post gradually merging into the angle thereof, the end plate and the posts being connected with the corrugations thereon engaged and interlocked.

3. The framing of a railway car, in combination with a metallic end plate having horizontal corrugations, and a pair of pressed-steel corner posts for attaching the edges of the plate to the framing, said posts each having angular flanges one of which is plane and the other corrugated on lines parallel to the corrugations of the end plate, the said flanges being spaced apart with a straight longitudinal groove in the interior angle of the post, the corrugations on each post gradually merging into the said groove in the angle of the post, the side margins of the end plate and the posts being connected with the corrugations engaged and interlocked.

4. In a railway car construction, a metallic end unit comprising a metal plate provided with parallel corrugations the length of which is co-extensive with the plate in which they are formed, in combination with a pair of corner posts attached one at each vertical margin of the plate, the said posts each formed as a flanged pressed-steel member one flange of which is corrugated on lines parallel to the corrugations of the end plate and the other flange of which is formed as a plane angularly disposed with relation to the corrugated flange, the end plate and corner posts being connected with their corrugations in interlocking engagement, with the vertical edges of the end plate clear of engagement with the plane surfaces of the posts.

5. In a railway car construction, a metallic end unit comprising a corrugated end plate, in combination with a pair of pressed-

steel corner posts, each of the said posts having a transversely corrugated flange and a plane flange angularly disposed with relation to the corrugated flange, the margins of the corrugated end plate engaging and interlocking with the corrugated flanges of the pair of posts and secured thereto with the vertical edges of the corrugated end plate clear of engagement with the angularly disposed plane flanges of the posts.

6. In a railway car construction, a metallic end unit comprising a pair of corner posts, said posts having corrugated flanges arranged in the same vertical plane and plane flanges extending in separated parallel vertical planes with the said plane flanges in angular relation to the corrugated flanges, with a longitudinal groove in the angle formed between a corrugated and a plane flange, and the corrugations of the post gradually merging into the groove thereof, in combination with an end plate having corrugations extending in planes parallel with the corrugation of the posts, the corrugated margins of the end plate engaging and interlocking with the corrugated flanges of the said corner posts and secured thereto with the vertical edges of the corrugated end plate clear of the angular surfaces of the plane flanges.

7. In a railway car construction, a paneled metallic end unit comprising a pair of pressed-steel corner posts, each having a straight longitudinal rib of semi-tubular cross-section upon the exterior angle and a correspondingly formed groove in the interior angle thereof, with corrugated flanges extending toward each other from the said semi-tubular sections in planes within the vertical plane formed by the meeting tangents of the said ribs, the corrugations of the flange gradually merging into the groove in the post, and a corrugated end plate having its side margins in interlocking engagement with and secured to the corrugated flanges of the pair of posts and lying within the said tangential plane.

8. In a railway car end construction, a pressed-steel corner post having angular flanges which stand in vertical planes 90° apart, one of said flanges being adapted for attachment to the side of the car and the other to the end thereof, the said last mentioned end flange being provided with corrugations which extend transversely from the edge of the post toward the angle thereof and are gradually merged thereinto.

9. In a railway car end construction, a pressed-steel corner post having a corrugated end flange and a side attaching flange angularly disposed with relation thereto, the corrugations of the end flange extending from the edge of the post toward the angle formed by the flanges and being gradually merged thereinto.

10. In a railway car end construction, a pressed-steel corner post having angular flanges spaces 90° apart with a straight longitudinal groove in the interior angle of the 5 post, one of said flanges being adapted for attachment to the side of the car and the other to the end thereof, the last mentioned flange being provided with transverse corrugations which gradually merge into the 10 said groove.

11. In a railway car end construction, a pressed-steel corner post having angular flanges which stand 90° apart, with a longitudinal groove in the interior angle of the 15 post, one of said flanges being formed as a plane surface for attachment to the side of the car, and the other to the end thereof, the said last mentioned flange being provided with corrugations extending from the edge 20 of the flange to the said groove and gradually merging thereinto.

12. In a railway car end construction, a pressed-steel corner post having a straight, longitudinal groove in the interior angle 25 thereof and a corresponding rib on the ex-

terior thereof, and a transversely corrugated lateral flange formed on the said rib, the corrugations of the flange gradually merging into the groove at the inner side of the flange.

13. A railway car end structure including a pressed-steel corner post having vertical side and end flanges arranged angularly with relation to each other to form at their convergence a straight groove extending 30 longitudinally of the post and a corresponding rib on the exterior thereof, the said end flange being transversely corrugated from its outer edge to the groove into which the corrugations gradually merge, and a corrugated 35 end plate attached to the post with the corrugations of the parts engaged and interlocked in fixed relation.

In testimony whereof I have signed my name at Milwaukee, this 12th day of April, 45 1921.

W. F. WOOLARD.
